FURNACE FOR HEATING FLUIDS

John Herman Rickerman, River Edge, N. J., assignor to The M. W. Kellogg Company, Jersey City, N. J., a corporation of Delaware

Application April 10, 1941, Serial No. 387,799

7 Claims. (Cl. 122—356)

This invention relates to the heating of fluids and to apparatus therefor, and is particularly concerned with the heating of hydrocarbon fluids by passage thereof through a plurality of interconnected tubes located in a combustion chamber.

In the design of oil heating furnaces of the latter type it is constantly necessary to reconcile as far as possible three essential requirements which are in conflict with each other. The cost of a furnace is to a great extent dependent upon its dimensions, each square foot of wall and roof area requiring the expenditure of a certain amount of money for the refractory or other material of which it is constructed and for the steel necessary for its support. The first requirement is therefore that a furnace be made as small as possible in order to reduce construction cost. Present methods of liberating heat by combustion being what they are, however, there is a limit to the amount of heat which can be released within a given cubic volume without the development of excessively high temperatures, which would hasten the disintegration of refractory and metal parts located therein and produce undesirable effects upon the fluid to be heated. The second requirement, therefore, is that the combustion chamber of a furnace be made sufficiently large to avoid destructively high temperatures locally thereof. To a certain extent the latter two requirements may be reconciled by employing special materials of construction which are exceptionally resistant to high temperatures—for example, chromium-molybdenum alloys. Such materials are a great deal more expensive than less durable ones, however, and if resorted to to any great extent will defeat any advantage gained with respect to the first two requirements. Hence, the third requirement is that all materials be as cheap as possible.

It is an object of the present invention to provide a generally new and improved furnace construction wherein the three requirements enumerated will be reconciled to a superior degree, in order that hydrocarbon oils may be heated more efficiently and at lower cost.

The furnace structure of my invention, in its preferred form, may be most readily characterized and distinguished visually from conventional types by its sloping side walls and its approximately triangular vertical cross-section. These features give the structure a shape which resembles that of a truncated or blunt wedge, resting upon its back with its truncated narrower

edge upward. It is contemplated by the invention to position parallel interconnected tubular conduits for fluids to be heated horizontally within the combustion chamber defined by the wedge-shaped structure, adjacent and substantially parallel to the sloping walls thereof. The invention further contemplates positioning additional fluid heating tubes within the combustion chamber adjacent the upper narrow portion thereof, so as to make up a tube bundle occupying the space between the converging side walls. Additional features contemplated by this preferred embodiment of the invention include a multiplicity of separate burners located in a horizontal plane parallel to and approximately coincident with the bottom of the combustion chamber. These burners are arranged in rows paralleling the fluid heating tubes and are provided with means for controlling the amounts of fuel supplied to the burners in the individual rows. Products of combustion travel upwardly from the floor of the combustion space, and after passing between and around the tube bundle in the converging portion emerge from the top of the combustion chamber into a suitable conduit leading to a stack.

The advantages of the furnace structure herein disclosed are many in number. Support for the refractory walls of the combustion chamber and for the tubes may be provided with exterior structural members having the so-called A-shape used in the bents of bridges and trestles which, as is well known, is superior from the standpoint of strength and rigidity. Aside from the purely load-supporting advantages of the wedge-shape construction, highly advantageous tube arrangements and methods of firing are thereby made possible. In prior known furnaces of more or less rectangular cross-section, no matter where the burners are located there is great irregularity and asymmetry in the distances of different tubes from the burners. In such furnaces the differing distances of the tubes from the burners cannot be compensated for by individual adjustment of the burners. It is impossible to liberate heat in the corners of a rectangular furnace if all the tubes are to be heated at a high and uniform rate, and such "dead spaces" reduce the mean rate of heat liberation for the furnace as a whole. In my improved furnace, however, there is a regular divergence between rows of tubes and rows of burners. Since the burner rows are individually controllable, I may regulate the amounts of fuel supplied to and lengths of the flames issuing from the burners in proportion to their distances from the tubes, and thereby liberate a maximum

amount of heat in all parts of the combustion chamber, without great variation in the rate of heating from tube to tube.

Other objects and advantages of the invention will appear during the course of the more detailed description now to be given with reference to the accompanying drawings, wherein:

Fig. 1 is an isometric view of the exterior of one embodiment of the invention;

Fig. 2 is an isometric view of a type of construction alternate to that of Fig. 1;

Fig. 3 is an isometric view of still another type of structure alternate to Figs. 1 and 2;

Fig. 4 may be considered a sectional end elevation of any one of the three furnaces shown in the first three figures showing one optional tube arrangement and the location of burners with respect thereto;

Fig. 5 is an isometric phantom view in detail of one type of burner assembly suitable for use in connection with the invention;

Fig. 6 is a purely diagrammatic representation of an alternate tube arrangement capable of being embodied in the structures shown in the preceding drawings, and

Figs. 7 and 8 are further diagrammatic tube arrangements exhibiting various features within the scope of the invention.

In Fig. 1 six I-beams 101 of which only four are visible, are arranged in two rows of three beams each, the beams of each row being parallel and inclined uniformly at an angle of approximately 25 to 35 degrees from vertical so as to include an angle of approximately 50 to 70 degrees between the two rows. Each beam in each row is connected to the corresponding beam of the opposite row by one of the three cross beams 102. The inclined beams 101 correspond in function to the buck stays used in conventional furnace construction and are mutually braced on either side by smaller beams 103 intermediate their length. The tops of beams 101 are additionally braced by members 104 so that the assemblage consisting of members 101 to 104 forms a supporting frame for refractory walls 105 and 109 enclosing a combustion chamber. A header box 106 has a counterpart concealed from view on the opposite end of the structure and covers the connections between the ends of tubes located along the sloping walls and adjacent the roof of the combustion chamber. Stack breechings 107 communicate with the interior of the combustion chamber and are adapted to convey products of combustion therefrom into the stacks 108.

It will be observed that the structure shown in Fig. 1 employs relatively short roof supporting members 102 by reason of its converging side walls. Their short length decreases their weight and cost relative to the roof members used in prior known furnaces having broad flat roofs.

In Fig. 2 the method of framing shown is identical to that of Fig. 1 comprising inclined members 201, top cross members 202, braces 203 and 204, refractory walls 205 and 209 and header boxes 206, but embodies a single bifurcated stack breeching 207 which surrounds the middle one of the three top cross members 202 while providing an air tunnel therefor to permit air cooling thereof. The construction of Fig. 2 may be employed when it is desired that only the one stack 208 be used.

Fig. 3 embodies a more extensive departure from the structures already described but still partakes of the advantages of the invention. In this structure the exit area for combustion prod-

ucts at the top of the combustion chamber is unobstructed by any structural members such as 102 and 202 as in Figs. 1 and 2. The weight of the refractory walls 305 and 309 is transmitted by the stays 301 and braces 303 to girders 304 extending along the tops of the inclined walls. The girders 304 in turn transmit the load to the main top cross members 302 at the extreme ends of the frame. An elongated stack breeching 307 collects products of combustion along the entire upper portion of the combustion chamber and conveys them to duct 308 which may lead to a stack or other apparatus such as an air preheater or economizer.

It will be understood that the furnace structure of my invention is not limited to the particular proportions and arrangements shown in Figs. 1 to 3. In general I may employ wedge-shape structures of varying lengths and heights and thereby provide furnaces of any desired capacity. When long furnaces are used the stack arrangement of Fig. 1 will be preferable, while with the shorter lengths the breechings of Figs. 2 and 3 may suitably be employed.

In Fig. 4, which, as previously mentioned, represents a sectional end elevation of any one of the structures shown in Figs. 1 to 3, the inclined beams 401 support refractory walls 410 and rest upon suitable footings 411. Tubes 412 are arranged in parallel rows longitudinally of walls 410 and hence appear in Fig. 4 as circles. Burners 413 are arranged in rows, only the ends of which are visible, and are individually controllable row by row as will be hereinafter more fully described, so that they may receive fuel at different rates and produce flames of graduated height as shown. Because of the locus of tubes 412 relative to the burners, they will receive heat predominantly by radiation and hence may be referred to as radiant tubes, in accordance with the usual furnace nomenclature. Tubes 414 are situated approximately at the apex of the section and are nested closely together so that hot products of combustion liberated by burners 413 must pass at relatively high velocity between and around them. They will receive heat predominantly by convection and are properly described as convection tubes.

The advantages of my improved furnace structure in enabling a maximum rate of heat liberation throughout a combustion chamber will be readily apparent from a view of Fig. 4. The centrally located rows of burners being farthest from heat absorbing surfaces may feasibly produce flames of greater intensity so as to effect a high rate of heat liberation in those regions of the combustion chamber not occupied by nor lying adjacent to any parts subject to overheating. At the same time the rows of burners at the sides of the combustion chamber may be fired less vigorously so as to protect the steel and refractory parts in close proximity thereto while utilizing the available volume for the liberation of appreciable quantities of heat. This arrangement facilitates systematic heat distribution to all the tubes of the sloping radiant banks. All the combustion products converge on the convection tubes 414 and acquire a high velocity by reason of the constricted upward passageway so that a maximum amount of heat can be recovered therefrom before release into the stack or stacks. In the particular tube arrangement shown in Fig. 4 fluid to be heated may be introduced into the interconnected rows of tubes in two parallel streams by way of inlets 419 and

withdrawn from outlets 418. It will be apparent that this tube arrangement insures that the two streams will be heated identically as the two streams traverse equal numbers of substantially equally heated tubes before leaving the furnace.

Fig. 5 illustrates one type of burner arrangement suitable for use in connection with the furnace of Fig. 4. 515 represents a slab or foundation of concrete or refractory of a length equal to that of a combustion chamber. This base is recessed or slotted as shown to provide support for the burner pipes 513 running longitudinally thereof. The burner pipes are provided with rows of orifices or jets along the upper surface thereof for the liberation of combustible material which enters the pipes from any suitable source by way of the projecting ends bearing the control valves 516. As will be seen the quantities of combustible material released by any one of the burner pipes may be individually controlled by means of the respective valves. Air for the combustion in controlled amount is supplied either by natural, forced, or induced draft through air ducts 517 extending perpendicularly of the burner pipes through the foundation slab 515 and opening into the recesses in which the burner pipes lie.

It is to be understood that the burner arrangement shown in Fig. 5 is purely exemplary as numerous other constructions for producing individually controllable rows of flames are known and may be adapted for use in connection with the invention.

In Fig. 6 I have shown an alternate tube arrangement for producing identical heating of two parallel fluid streams wherein a greater number of tubes are used in the convection bank. The radiant tubes 610 are disposed as in Fig. 4 but the convection tubes 614 fill in the apex of the combustion chamber relatively completely. The arrangement in Fig. 6 in comparison with that of Fig. 4 illustrates how the relative sizes of the radiant and convection sections may be varied within a given furnace volume.

All the usual methods of adjusting the rate of heating of a fluid stream or streams may be available of in connection with my improved structure as, for example, the use of double rows of tubes in a radiant bank. Such an arrangement is shown by Fig. 7 as it might be used to heat a single fluid stream. The radiant tubes 710 are conventionally arranged but the convection section embodies a feature of the invention which may be of particular value when a high efficiency is desired in a relatively small convection section. As indicated by the figure, convection tubes 714 have been arranged in a relatively narrow bundle centrally located within the apex of the structure. What would normally be free space on either side of the bundle is filled in with refractory so that products of combustion are required to traverse a relatively constricted path through the convection tube bundle. By this means a higher velocity and improved heat transfer is afforded. Moreover by stepping in the refractory filler as shown and making the tube bundle progressively narrower with height, the combustion gases are given an increasing velocity concurrent with lowering of their temperature by heat transfer. In this manner the tendency for heat transfer to decrease with temperature may be counteracted and heating made more uniform throughout the convection bank.

Fig. 8 illustrates still another modification of the tube arrangement contemplated by the in-

vention and shows the manner in which differing conditions may be maintained on the two sides of the combustion chamber, in accordance with a difference in the number of tubes and the rate of heat transfer desired therein. Radiant tubes 810 are arranged in a single row along the entire height of the left hand wall of the furnace while on the right hand wall they are arranged in a double row which does not extend all the way to the base. A bridge wall 820 minimizes cross-radiation between the two sides of the furnace. Convection tubes 814 are arranged compactly in a manner alternate to that of Fig. 7 between projecting refractory corbels to provide higher velocity and increased heat transfer for the products of combustion passing therethrough.

The improved furnace construction of my invention is capable of receiving a variety of mechanical expressions and may incorporate a greater number of separate fluid heating circuits in any one furnace than have been indicated in the drawings. While not limited thereto, my invention is of particular advantage in connection with hydrocarbon conversions effected at elevated temperatures such as thermal and catalytic cracking, polymerization, reforming and the like. It may advantageously be used to heat hydrocarbon oils prior to distillation thereof and may incorporate in a common combustion chamber both oil heating and steam generating coils. It is to be understood furthermore that I am not limited by any of the examples given herein for purposes of illustration.

I claim:

- 35 1. In a furnace for heating fluids, the combination which comprises a combustion chamber having a floor, a furnace wall bounding said chamber and inclined inwardly with respect thereto, a plurality of fluid-conducting conduits disposed adjacent said wall, a plurality of burners located in said floor and adapted to project products of combustion upwardly directly therefrom toward said wall, and means for controlling the firing of said burners to effect less intensive firing of said burners closest to said inclined walls than those farthest from said inclined walls.
- 20 2. A furnace as in claim 1 wherein said wall extends substantially to the level of said floor.
- 25 3. A furnace for heating fluids comprising a combustion chamber bounded on two opposite sides by converging walls, conduits adjacent said walls, a plurality of burners positioned between the edges of said walls which are farthest apart and adapted to project combustion products generally toward the convergence of said walls, and means for controlling the firing of said burners to effect less intensive firing of said burners closest to said sloping walls than those farthest from said sloping walls.
- 30 4. A furnace as in claim 3 wherein said edges are the lower edges of said walls and said burners are directed vertically upward.
- 35 5. A furnace for heating fluids comprising a furnace floor, two side walls rising upwardly and inwardly toward each other at acute angles from two opposite sides of said floor, two end walls rising from the other two opposite sides of said floor, said four walls and said floor enclosing a combustion chamber having a relatively broad base and a relatively narrow opening for the escape of combustion products between the uppermost edges of said inclined side walls, corbels projecting inwardly from said side walls just below said opening so as to enclose between them a narrowed passage for combustion products ap-

proaching said opening, a plurality of interconnected conduits for fluids disposed adjacent and parallel to said side walls, a plurality of like conduits relatively compactly disposed within said passage, a plurality of burners adapted to produce hot products of combustion for said combustion chamber and means for controlling the firing of said burners to effect less intensive firing of said burners closest to said rising walls than those farthest from said rising walls.

6. A furnace for heating fluids which comprises a combustion chamber having a plurality of upwardly directed burners located in the floor thereof, the area of said floor being greater than the horizontal cross-sectional area of said chamber at any level appreciably above said floor, sloping refractory walls bounding two sides of said chamber and having a relatively narrow opening between their uppermost edges for the escape of combustion gases, a plurality of fluid-conducting conduits disposed adjacent said refractory walls.

and means for controlling the firing of said burners to effect less intensive firing thereof closest to said sloping walls than those farthest from said sloping walls.

- 5 7. A furnace for heating fluids which comprises a combustion chamber limited in one direction by a burner setting, a plurality of inwardly-directed burners in said setting, the cross-sectional area of said chamber in a plane coincident with said setting being greater than in any parallel plane appreciably distant from the plane of said setting, sloping refractory walls bounding two sides of said chamber in other directions and provided with an opening opposite said burner setting for the escape of combustion products, a plurality of fluid-conducting conduits disposed adjacent said walls, and means for controlling the firing of said burners to effect less intensive firing thereof closest to said sloping walls than those farthest from said sloping walls.
